UNITED STATES PATENT OFFICE.

CLINTON ALVORD, OF WORCESTER, MASSACHUSETTS, ASSIGNOR, BY MESNE ASSIGNMENTS, TO THE PRESTON HOSE AND TIRE COMPANY, OF MAINE.

LOOM.

SPECIFICATION forming part of Letters Patent No. 645,637, dated March 20, 1900.

Application filed July 19, 1899. Serial No. 724,342. (No model.)

To all whom it may concern:

Be it known that I, CLINTON ALVORD, of Worcester, in the county of Worcester and State of Massachusetts, have invented certain new and useful Improvements in Looms, of which the following is a specification.

This invention consists of a loom having a lay provided with a plurality of shuttle-races, shuttles mounted therein, each of said shuttles operatively connected with an independently-operated shuttle-actuating rack, and means for operating each of said racks to positively operate said shuttles, all as hereinafter more fully set forth in the following description, and the novel features of which are particularly pointed out and clearly defined in the claims at the close thereof.

In the following description reference is had to the accompanying drawings and to the letters marked thereon, like letters designating the same parts or features throughout the several views.

Of the drawings, Figure 1 is a front elevation of a loom embodying this invention, portions thereof being represented as broken away to more clearly illustrate the invention. Fig. 2 is a side elevation of the loom shown in Fig. 1. Fig. 3 is a detail of one of the shuttles.

Referring to the drawings, A represents the frame of a loom, B the driving or crank shaft journaled therein, and C one of the cranks to which is connected one end of a link D, the opposite end of which is connected with the lay E. The lay-beam F is provided with a reed or batten G, at each side of which are located shuttle-races a b c, within which are arranged the shuttles a' b' c', respectively. The shed for the shuttle a' is represented at a², and the harness-frames a³ control the warp-threads which form this shed. The shed for the shuttle b' is represented at b², and the harness-frames b³ control the warp-threads which form this shed. The shed for the shuttle c' is represented at c², and the harness-frames c³ control the warp-threads which form this shed.

The three shuttles a' b' c' operate to each weave a separate fabric independent of the other shuttles, and in order to unite the fabric produced by the shuttle b' with the fabric

produced by the shuttle a' an independently-controlled set of warps are incorporated in the fabric, which stitch the two fabrics together, and said stitching-warps are controlled by a harness-frame e, which is so operated that the shuttle b' lays its weft under said stitching-warps, and said frame e is then lowered, so that the shuttle a' lays its weft over said stitching-warps, and then said warps are raised up, so as to overlie and engage the weft of the shuttle b' again, and so on throughout the weaving process. The fabric produced by the shuttle c' is likewise secured to the fabric produced by the shuttle b' by means of another set of stitching-warps controlled by a harness-frame d.

In the form of my invention herein shown and described I have shown a loom equipped with three shuttles, although it is to be understood that it is within the scope of the present invention to construct a loom of this character having only two shuttles, their respective harness-frames, and an additional harness-frame adapted to control an independent set of stitching-warps which engage both weft-threads and are incorporated in the fabric during the process of weaving, or in some instances more than two shuttles may be employed.

Fig. 3 shows a plan view of the upper shuttle c', and said shuttle is formed with a recess f¹ for receiving the bobbin f², from which latter the yarn passes out through an eye f³. Each shuttle is formed or provided with a rack f⁴ on one side thereof, and in the shuttle c' the said rack is located on the upper side thereof. The shuttles b' and c' are also formed with racks b⁴ c⁴, respectively, said racks being located on the under side of said shuttles.

g g represent pinions or toothed wheels which are mounted upon pins g², and the teeth of said pinions project into the shuttle-race c and are adapted to engage with the rack a⁴ of the shuttle a'. The pinions g also engage with a rack g³, which is mounted to slide freely in a channel or way g⁴, provided in the lay-beam F, and means hereinafter described are provided whereby said rack is moved longitudinally to rotate the pinions g and through the medium of said pinions move

the shuttle a' back and forth across the bat-
ten or reed G . Similar racks g^31 and g^32 are
likewise mounted in the lay-beam F , and said
racks engage, respectively, with pinions g^6
and g^5 , which latter mesh with the racks f'
and b' , provided on the shuttles b' and c' .
Each rack is operated from the main crank-
shaft B by means of mechanism which is con-
structed and arranged as follows:

10 Upon a frame A' is journaled a counter-
shaft k , which has fixed on its inner end a
gear k' , that meshes with a pinion k^2 , fixed
to the crank-shaft B . Upon the shaft k are
fixed three cams k^3 , each formed with a cam-
15 slot k^4 , into each of which slots k^4 projects a
cam roll or truck l , mounted upon a lever l' .
Each lever l' is fulcrumed upon a bar or rod l^2 ,
mounted in the frame A' , and is formed with
oppositely-extending arms l^3 and l^4 . The arm
20 l^3 of each lever l' has a loop l^5 loosely connected
therewith at the extremity thereof, into which
is hooked one end of an adjustable connection
comprising the bars m m' , which are formed
with right and left screw-threads and the turn-
25 buckle m^2 , and to the opposite end of said
connection one end of a flexible strap n is con-
nected. The opposite end of the strap n em-
braces a drum n' , mounted to turn freely upon
a bar o , which is supported by stands o' o' .

30 Compounded with the drum n' is a drum n^2 ,
to which is secured one end of a strap p , which
extends upwardly over a sheaf q , mounted
upon the lay, and has its opposite end secured
to the end of the rack g^31 , which operates the
35 shuttle b' through the medium of the pin-
ions g^6 , hereinbefore referred to, and when
the strap p is drawn downwardly the rack g^31
is moved in one direction—that is, to the left
40 in Fig. 1. The arm l^4 of the lever l' is like-
wise connected with one end of a strap n^3 , the
opposite end of which strap embraces a drum
 n^4 , mounted loosely upon the bar o . Com-
pounded with drum n^4 is a drum n^5 , to which
45 is secured one end of a strap p' , which extends
upwardly over a sheaf q' , mounted upon the
lay, and has its opposite end secured to the
rack g^31 at a point intermediate its ends, so
that when the strap p' is drawn downwardly
50 said rack is moved to the right in Fig. 1. As
the straps p and p' are controlled and oper-

ated by the opposite arms of the lever l' when
said lever is moved, the drums n^2 and n^5 will
be rotated in opposite directions and one of
the straps p or p' will be drawn downwardly
and will positively move the rack g^31 in one 55
direction of its movement, while the other
strap will be unwound from its drum in pro-
portion and be free to move upwardly as said
rack is moved. The racks g^31 and g^32 are each
likewise connected with a lever l' , mounted 60
upon the bar l^2 , and each of the said levers l'
is actuated by a separate cam k^3 , and the dif-
ferent cams k^3 may be so timed that the shut-
tles a' b' c' may be operated in unison suc-
cessively or as desired. The cams k^3 are so 65
formed that after each movement of the lever
 l' , or, in other words, after each pick of the
shuttle actuated thereby, there is a period of
rest, during which time the batten beats the
weft up against the fabric and returns for the 70
next pick.

What I claim, and desire to secure by Let-
ters Patent, is—

1. In a loom, the combination of a lever piv-
oted intermediate its ends, means for vibrat- 75
ing said lever, independent compound drums,
strap connections between corresponding
members of said drums and the opposite ends
of said lever respectively, a reciprocatory
shuttle-actuating slide, and straps connecting 80
the same with the other members of said com-
pound drums, respectively, substantially as
described.

2. In a loom, the combination of one or more
shuttle-actuating slides, straps connected with 85
each slide, compound drums independently
rotatable and having said straps connected
respectively with corresponding members, a
lever pivoted intermediate its ends, strap con-
nections between the other corresponding 90
members of the compound drums, respec-
tively, and the opposite ends of said lever, and
a wheel having a cam-groove occupied by a
part of the lever, whereby the latter is vi-
brated, substantially as described.

CLINTON ALVORD.
